(57) **CLAIM**

The ornamental design for a combined electronic input device and display, as shown and described.

DESCRIPTION

FIG. 1 is a front perspective view of a combined electronic input device and display showing our new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a cross-sectional view taken through line 7-7 of FIG. 2; and,

FIG. 8 is a cross-sectional view taken through line 8-8 of FIG. 2.

The broken lines consisting of unevenly sized dashes define the boundary of the claim, which extends to the boundary but does not include the boundary. The even-length broken line showing of the remainder of the display illustrates environmental structure and forms no part of the claimed design.
